MARK J. BRIAR, OF OXFORD, INDIANA.

Letters Patent No. 70,794, dated November 12, 1867.

IMPROVED GATE-LATCH.

The Schedule referred to in these Letters Patent and making part of the same.

TO ALL WHOM IT MAY CONCERN:

Be it known that I, MARK J. BRIAR, of Oxford, in the county of Benton, and State of Indiana, have invented a new and improved Latch for Gates, &c.; and I do hereby declare that the following is a full, clear, and exact description thereof, which will enable others skilled in the art to make and use the same, reference being had to the accompanying drawings, forming part of this specification.

The present invention consists in a novel arrangement of a lever-latch for gates, &c., whereby a person can open the gate from either the inside or outside without reaching over the top of the same. In the accompanying plate of drawings my improved latch for gates is illustrated—

Figure 1 being a front elevation of a gate having it applied thereto, and

Figure 2 an elevation of a gate-post, showing the latch-lever hung thereon, and its connecting parts.

Similar letters of reference indicate like parts.

A, in the drawings, represents a gate, which, in form, shape, and size, may be of any style now in common use.

This gate, by one side, B, is hung on hinges, C, to a post, D, so as to swing thereon in one direction, it being held from moving in the opposite direction by the stop-pin E to the other gate-post F. G, a stud or pin, on one side of gate A, next to the post F, against which the latch-lever arrangement, to be now described, sets, and holding the gate from being opened until raised therefrom, as will be hereinafter described. H, a loop or clasp, fixed to gate-post F on a horizontal plane, I, an angular-shaped catch hung at one end to guide or clasp H, from which, passing down and thence up through the said clasp by its arm J, it is, at its upper end, hung through a link-piece, K, to a lever-handle, L, at one side of its fulcrum-point M. This lever-handle projects from both sides of the gateway, and plays through a loop or guide, N, suitably arranged therefor on the gate-post F, to which it is hung.

From the above description of my arrangement of a gate-latch, it is plainly obvious that the latch can be operated from both sides of the gate, whether outside or inside.

I claim as new, and desire to secure by Letters Patent—

A latch, for gates, &c., composed of latch-lever I, link-piece K, lever-handle L, arranged together substantially as and for the purposes described.

MARK J. BRIAR.
